[57] CLAIM

The ornamental design for an ink jet print head module, as shown.

DESCRIPTION

FIG. 1 is a perspective view of an ink jet print head module showing our design;

FIG. 2 is a front elevational view of the module;

FIG. 3 is a rear elevational view of the module;

FIG. 4 is a side elevational view of the module as seen looking generally right to left in FIG. 1;

FIG. 5 is a side elevational view of the module as seen looking generally left to right in FIG. 1;

FIG. 6 is a plan elevational view of the module; and

FIG. 7 is a bottom elevational view of the module.
